UNITED STATES PATENT OFFICE

EUGENE M. COLE, OF CHARLOTTE, NORTH CAROLINA

RIDGING OR MILLING MACHINE

Application filed December 1, 1927. Serial No. 237,042.

My invention relates to a ridging machine, in which I have provided means for mounting adjustable ridging devices on the rear end of a ridging machine in such a manner that the 5 contour of the ridge made by the ridging devices may be regulated.

An object of my invention is to provide a 10 ridging machine having adjustable ridging devices secured on the frame of the ridging machine together with means for adjusting the position and angularity of the ridging devices.

Another object of my invention is to provide a frame with adjustably mounted ridging means, together with means for setting the angle of the ridging means, and means for holding the ridging means in adjusted 15 position.

Another object of my invention is to provide a frame with ridging means adjustably mounted on the frame, said ridging means being capable of being adjusted away from and towards each other, together with means for regulating the angularity of the ridging 20 means, the adjusting means for the angularity of the ridging means being adapted to co-operate with the means for adjusting the ridging devices away from and towards each other, so that regardless of the adjusted positions of the ridging means along the frame, the angle adjusting means will operate to impart the same angular adjustment to the ridging means in all of their adjusted positions along the frame.

Some of the objects of my invention having been stated, other objects will appear, as the description proceeds, when taken in connection with the accompanying drawings, 25 in which—

Figure 1 is a side elevation in perspective of my ridging machine equipped with adjustable disks;

Figure 2 is a rear elevation in perspective 30 of the structure set forth in Figure 1;

Figure 3 is a side elevation in perspective of my ridging machine, showing the same equipped with inthrow plows;

Figure 4 is a rear elevation in perspective 35 of the structure set forth in Figure 3;

Figure 5 is a plan view of the means for holding the disks in adjusted position;

Figure 6 is a side view of one of the braces for the plows as shown in Figures 3 and 4.

Referring more particularly to the drawings, the numerals 10 and 11 indicate the main frame portions of my milling machine, which have a clevis member 12 secured between the front ends thereof, and these members have secured thereto downwardly projecting members 13, only one of the same being shown in the drawings, and between these members 13 a ground wheel 14 is secured, which ground wheel drives a rod 15 which actuates to oscillate bottom (not shown) of the guano distributor. The members 10 and 11 project rearwardly and have secured there between a guano hopper 16 and to the rear end of the members 10 and 11 is secured a cross piece 17, the members 10 and 11 being secured intermediate the ends of member 17 and secured to the ends of the members 17 and running forwardly are brace members 18 and 19, which members are secured to the members 10 and 11 at a point immediately 40 in front in the hopper by means of bolts 20. The members 21 and 22 are secured on either side of the frame to the members 18 and 11, and 19 and 10 respectively. These members 21 and 22 have a hole 90 through their central portion which is adapted to receive the end 23 of member 24, the end 23 having a hole therethrough in which a cotter pin is adapted to be received to hold the member 24 in position. This member 24 is used only 45 in Figures 3 and 4 and it will be described more fully in describing those figures.

Handle members 25 and 26 are secured to the forward portion of the members 10 and 11, and upright members 27 and 28 are secured to the rear portion of the members 10 and 11 and project upwardly where they are secured to the handle members.

The members 17 has a plurality of holes 50 therein in which holes the ridging members are adapted to be adjustably secured. In Figures 1 and 2 I have shown my ridging machine equipped with adjustable disk members. These disk members are secured to the member 17 by having bearing members 31 55

and 32 adapted to be secured to the member 17 by means of bolts 33 piercing the bearing members and also piercing the member 17 and these bearing members hold vertically disposed shafts 34 and 35 and to the lower end of these shafts are secured in a conventional manner disks 36 and 37 and to the upper ends of the shafts 34 and 35 are secured members 38 and 39, which members 10 project rearwardly and have holes 40, 41 and 42 therein in which hooked rod members 43 and 44 are adapted to be adjustably secured. Secured to the middle portion of a member 17 is the member 45, which member 15 is secured to the member 17 by means of a bolt 46 piercing a slot 47 in the member 45. This member 45 projects forwardly over the member 17 and has rotatably secured therein a shaft 47a which has a member 48 secured 20 thereon, this member 48 having crankarms 49 and 50 and the ends of these crank arms 49 and 50 have holes therein for the reception of the rods 44 and 43 respectively. Secured between the handle members is a spanning member 52 which is secured to the handle members by the same bolts 53 which 25 secure the uprights 27 and 28 to the handle members and secured to the central portion of this member 52 is a semi-circular member 30 54, which is secured to the member 52 by means of bolts 55 and 56. This member 54 has a slot 56 therein in which a forked member 57 is adapted to be adjustably secured by means of a bolt 58. To the upper end of the 35 rod 57 is pivotally secured, as at 58a, a handle member 59, which handle member is adapted to be secured in the forked member 57 to hold the disks 36 and 37 in adjusted position, and when the handle 59 is swung around to 40 the opposite side of that shown in Figure 2 it will be passed over a projection 60, which will hold the disks in parallel relation with each other when it is desired to transport my combined guano distributor and ridging machine from place to place. The members 38 45 and 39 have secured thereto by means of bolts 61 and 62 scraper members 63 and 64.

When it is desired to use plows instead of disks on my ridging machine, the bolts 33 are 50 removed and the disks 37 and 38, shafts 34 and 35, housings 31 and 32, members 38 and 39 and the rods 43 and 44 are removed and this angle adjusting structure may be left on the frame or removed and it is shown as being 55 removed in Figures 3 and 4. In place of the disk members L-shaped members 70 and 71 which have slots 72 and 73 therein are secured to the member 17 by means of bolts 74 and 75, and these L-shaped members 60 have corrugated legs 76 and 77 on the outer sides of which are adapted to be secured plow foot members 78 and 79 by means of bolts 80 and 81 and to the lower end of the foot members the plows 82 and 83 are 65 adapted to be secured and intermediate the

ends of the plow foot members are secured the members 24, which members extend forwardly and are secured in the members 21 and 22, and these members 24 serve as a brace for the plow-foot members. By means 70 of the holes 30 and the slots 72 and 73, these plow-foot members may be adjusted in any desired position along the member 17.

The member 45 is located midway between the ends of the member 17, and each end portion of the member 17 has the sets of holes 30 therein, some of the holes 30 being obscured by the housings in the drawings. Two bolts 33 are adapted to be secured in two of these holes 30 to secure the housings in 80 place. These holes 30 are so arranged in sets that when the housings are placed in any set of holes that the angling means when set at a predetermined point on the member 54, will 85 impart the same angularity to the disks, regardless of which sets of holes 30 the housings are placed in. This is done of course in cooperation with the holes 40, 41 and 42 in the crank members 38 and 39, as when the housings are adjusted in the middle set of 90 holes, as shown in Figures 1 and 2, the rods 43 and 44 are secured in the holes 41, and when the housings are secured in the outer set of holes on the member 17, the rods 43 and 44 are placed in the holes 40, and for the inner 95 adjustment, the rods are placed in the holes 42. In this way the angularity of the disks will be the same at the same adjustment point on the member 54, regardless of their position on the member 17. 100

In the drawings and specification I have set forth a preferred embodiment of my invention, and although specific terms are employed, they are used in a generic and descriptive sense only, and not for purposes of limitation, the scope of the invention being 105 set forth in the appended claims.

I claim:

1. In a ridging machine, a framework, 110 housings mounted on the rear end of the framework, said housings being adapted to be adjustably secured in any desired position laterally on the framework, vertically disposed rotatable shafts mounted in the housings, disks mounted on the lower ends 115 of the shafts, crank arms mounted on the upper ends of the rotatable shafts, an adjusting shaft vertically mounted in the framework, two integral crank arms fixedly secured on the adjusting shaft, rods extending from 120 the crank arms on the rotatable shafts to the crank arms on the adjusting shaft, a lever secured to the upper end of the adjusting shaft, and means associated with the adjusting lever for holding the rotatable shafts and associated parts in adjusted 125 position.

2. In a ridging machine, a frame work, a transverse cross member secured to the rear end of the frame work laterally adjustable 130

5   housings mounted on the cross member, vertically disposed rotatable shafts mounted in the housings, inthrow disks mounted on the lower ends of the said rotatable shafts, crank-
 10   arms having a plurality of holes therein secured to the upper ends of the rotatable shafts, a vertically disposed shaft secured in the frame work and having two crankarms fixedly secured thereon, rods adjustably and
 15   removably secured in the crankarms on the vertically disposed disk bearing shafts, and means associated with the frame work for adjusting the angularity of the disks simultaneously and for holding the disks in adjusted position.

20   3. In a ridging machine, two forwardly converging frame members, a cross piece secured to the rear end of the frame members, said cross piece projecting beyond the junction point of the converging frame members and the cross member, the forward end of the frame member having a clevis secured there between, a ground wheel secured between the converging frame members additional frame members secured to the ends of the cross member and converging inwardly to the point intermediate the ends of the frame members where they are secured there-
 25   to, a plurality of holes in the cross member, a plurality of ridging devices adapted to be adjustably secured along the cross member, and means for simultaneously adjusting the ridging devices.

30   4. In a milling machine, a framework, a laterally disposed member on the rear end of the framework, formed with laterally spaced sets of holes, ridging members adapted to be secured in any one of the sets of holes, said ridging means comprising rotatable disks
 35   40   mounted on rotatable shafts, crank arms secured to the upper ends of the disk bearing shafts, a plurality of holes in the crank arms, an adjusting device mounted on the framework and having rods extending therefrom to be loosely connected in any one of the sets of holes in the crank arms on the disk-bearing shafts, the holes in the laterally disposed member being so placed that when the disk bearing shafts are moved to a new set of
 45   50   55   50   holes and the adjusting device set at a pre-determined point and the rods between the adjusting device and the crank arms set in a selected set of holes in the crank arms that the angle of the disks will remain the same regardless of which set of holes the disk bearing shafts are mounted in on the laterally disposed member.

60   5. An agricultural implement having a framework, a supporting wheel mounted at the forward end of the framework, a transversely disposed bar associated with the rear end of the framework, a plurality of holes in said bar, two housings being adapted to be adjustably mounted in said holes, vertically disposed disc bearing shafts rotatably mount-

ed in said housings, discs rotatably mounted on the lower ends of said disc bearing shafts, crank arms fixedly mounted on the upper ends of said disc bearing shafts, a vertically disposed rod having two crank arms thereon, connecting rods running between the crank arms on the vertically disposed shaft and the crank arms on the disc bearing shafts, means for twisting the vertically disposed shaft to regulate the adjustment of the said discs, said discs being adapted to be adjusted into a position parallel with the front wheel to act as rotatable supports for the framework.

65   6. In a hillng and ridging machine, a framework, a laterally disposed member formed with laterally spaced sets of holes and being secured on the rear end of the framework, a pair of rotatable disks adapted to be secured in corresponding sets of holes in the laterally disposed member, unitary means for simultaneously adjusting the angularity of the disks, the adjusting means being adapted to cooperate with the disks when secured in corresponding sets of holes along the laterally disposed member to angle the disks to the same degree regardless of the position of the disks along the laterally disposed member.

In testimony whereof I affix my signature.

EUGENE M. COLE.
